UNITED STATES PATENT OFFICE

2,009,837

TUBULAR HEAT EXCHANGER FOR LIQUIDS

Harvey Feldmeier, Little Falls, N. Y., assignor to
Cherry-Burrell Corporation, Wilmington, Del.,
a corporation of Delaware

Application May 4, 1934, Serial No. 723,949

8 Claims. (Cl. 257—183)

This invention relates to tubular surface heat exchangers for liquids, and more particularly to improvements in tubular heat exchangers adapted for cooling or heating liquids such as milk.

- 5 Devices embodying the improvements are adapted for different purposes, such as for milk to milk regeneration, in which the exchange of heat occurs between milk circulating through the tubes and milk flowing over the outer surfaces thereof, 10 and for cooling or changing the temperature of milk flowing over the outer surfaces of the tubes by circulating water, brine, ammonia or other suitable medium through the tubes.

Heat exchangers of this sort, adapted for heating and cooling milk, commonly comprise a bank of horizontal tubes arranged one above another and connected at their ends by return connections or headers to join the tubes into a continuous coil or passage for the flow of a fluid medium, 20 and means for causing milk or other liquid to flow in thin films over the outer surfaces of the tubes. Ordinarily the tubes are provided with drip strips extending longitudinally along their bottoms to properly direct the surface films from one tube

25 onto the next tube below. In addition, the tubes are commonly provided adjacent their opposite ends with drip rings for preventing the surface films from spreading lengthwise along the tubes beyond desired limits and from reaching the end supports for the tubes or the headers, and also

30 to prevent possible contamination of the surface liquid being cooled or heated by contact with any cooling or heating medium which may leak through the joints of the coil.

35 A primary purpose of my invention is to construct a heat exchanger of this character so as to enable the quick and easy removal of any tube or tubes thereof without taking down the whole coil or disassembling or disturbing other

40 tubes or parts of the device. This possibility of removing one or more of the tubes with the minimum disassembly or disturbance of the parts of the exchanger is an important consideration, particularly in large plants where such heat ex-

45 changers are run many hours a day and are subject to severe expansion and contraction strains, usually unequal in different parts of the device, due especially to the use of steam in sterilizing the exchangers. These strains often loosen

50 the solder joints for the drip strips or drip rings, and it is very inconvenient and difficult to make the necessary repairs with the tubes in place in the device, whereas the repairs could be quickly and easily made if the defective tube or tubes

5 of one extra tube for a heat exchanger in a large plant will practically insure against trouble or shut-down, since a defective tube can be quickly replaced by the extra tube and the apparatus continued in operation while the defective tube is being repaired.

Another object of the invention is to provide a tubular heat exchanger for liquids having the other features of advantage and improvement hereinafter described and set forth in the claims. 10

In the accompanying drawings:

Fig. 1 is a fragmentary, longitudinal, sectional elevation of a tubular surface heat exchanger of one construction embodying my invention.

Fig. 2 is a sectional plan showing one of the 15 tubes disconnected from its return connectors and shifted out of normal position to illustrate the manner of removing a tube.

Fig. 3 is a transverse, sectional elevation on line 3—3, Fig. 1.

20 Figs. 4 and 5 are fragmentary, longitudinal, sectional elevations of different, slightly modified constructions embodying the invention.

Fig. 6 is a fragmentary, longitudinal, sectional elevation on a larger scale, showing a portion of 25 the tubes and the manner of connecting and removably mounting the same.

Fig. 7 is a fragmentary, longitudinal sectional elevation showing one end of a tube partly removed.

30 Referring first to the construction shown in Figs. 1 to 3 and 6, 10 represents the horizontal heat exchange tubes arranged in a bank one vertically above and parallel with another, these tubes being removably mounted in this relation, 35 as presently described, in upright supports or panels 11 adjacent opposite ends of the tubes stationarily mounted on and supported by a suitable base 12.

The several horizontal tubes are connected with 40 each other to form a continuous coil or passage for the flow of a fluid through the several tubes by suitable headers or return connectors at the opposite ends of the horizontal tubes. Means, not shown, of usual or suitable construction deliver milk or other liquid at the top of the bank 45 of tubes so as to cause it to flow in films down over the outer surfaces of the tubes for exchange of heat with the medium circulating in the tubes.

13 is the usual bottom trough for catching the 50 liquid that flows over the tubes. The horizontal tubes shown are provided with the usual drip strips 14 extending longitudinally along the bottoms of the tubes, and the tubes are also shown as provided with downwardly converging drip 55

5 rings 15 at the opposite ends of the drip strip 14 to confine the liquid on the outer surfaces of the tubes between these rings and prevent it from travelling or creeping beyond the rings toward 10 the ends of the tubes. Drip rings 16 are also shown on the tubes outwardly beyond the rings 14 and diverging therefrom downwardly, these rings being for the purpose of preventing any condensation on the ends of the tubes outwardly 15 beyond these rings, or any liquid that may leak through the joints between the tubes and their connectors from creeping inwardly on the tubes and contacting with and contaminating the surface liquid being cooled or heated.

15 The tubes 10, see Fig. 1, are removably connected at one end thereof to return connectors 17 by gland nuts or bushings 18 which surround and are adapted to turn about the tubes and screw into threaded holes in the connectors 17. At 20 their other ends the tubes are similarly secured in connectors 19 by gland nuts or bushings 20 which have threaded ends which screw into the threaded end openings of the connectors 19. These gland nuts or bushings 18 and 20 pass 25 loosely through holes 21 in the end panels 11 and are adapted to rest or bear in these holes for supporting the tubes.

The connectors may be of different constructions and different means may be employed for 30 forming fluid tight joints between the same and the tubes, depending upon the use to which the exchanger is to be put and the medium which will be used in the coil. For instance, if the device is to be used for a milk to milk regenerator in which 35 milk flows through the tubes for exchange of temperature with milk flowing over their outer surfaces, then the connectors should be constructed so that they can be readily opened for cleaning out and sterilizing the tubes, whereas if a medium, 40 such as water, brine or ammonia flows through the tubes, simple connectors not adapted to open can be employed. The means for sealing the joints between the connectors and the tubes should be of a character suitable for use with the 45 particular medium which flows through the tubes. As shown in Fig. 1, the connectors 17 and 19 are in the form of simple return bends. In Fig. 6 the connector 19a shown at the left hand end of the exchanger is suitable for a milk to milk regenerator, and is provided with a hinged or movable cap 22 which is releasably secured in closed 50 position by clamping means 22a of known or suitable construction adapting the cap to be opened for cleaning the tubes, and the joints between the tubes and these connectors are preferably formed by taper metal rings or gaskets 23 on the tubes adapted to be forced against taper seats in the connector by the screw gland nuts or bushings 20. The connectors 17 and 17a shown at the 55 opposite ends of the tubes in Fig. 6 are of the simple return bend form and the joints between the connector 17 and the two uppermost tubes are formed by lead gaskets 24 which are clamped between the ends of the tubes and seats in the 60 connector by screwing up the gland nuts 18 which bear at their inner ends against fixed rings 25 on the tubes. This construction is suitable for a direct expansion exchanger in which ammonia is used in the tubes. The other connector 17a shown at the right hand end in this figure is 65 similar to the upper connector but the joints between the same and the tubes may be formed by suitable packing gaskets 26 surrounding the tubes and compressed against taper seats in the connector by the gland nuts or bushings 18.

If it is necessary to remove one of the tubes 10 for any reason, the connectors at the opposite ends of this tube are disconnected therefrom by unscrewing the bushings 18 and 20, leaving the tube freely supported by the bushings at its opposite ends in the holes 21 in the end panels. The tube can then be shifted endwise in one direction, for instance, to the left, in the holes 21, until the opposite or right hand end of the tube is clear of the hole in the right hand panel. Then 10 this end of the tube can be moved obliquely forwardly or rearwardly to clear the right hand panel, as illustrated in Fig. 2, after which the tube can be pulled lengthwise thereof out of the hole in the panel at the opposite end of the 15 exchanger. This tube can be replaced by another tube by a reversal of this procedure and the new tube secured to the connectors by tightening the gland bushings thereon, thus permitting the use of the exchanger while necessary 20 repairs are being made to the tube which has been removed. The outer drip rings 16 on the tubes are of small enough diameter to pass through the holes 21 in the end panels to permit such shifting, removal and replacing of the 25 tubes.

The modified construction shown in Fig. 5 may be the same as the construction above described with the exception that instead of employing gland bushings which extend through 30 the holes in the end panels for supporting the tubes in the holes, the gland nuts 27 are made shorter and separate bushings or sleeves 28 are provided on the tubes for supporting the tubes in the holes in the end panels. These supporting or bearing bushings 28 may be suitably secured on the tubes, as by set screws 29.

In the other modification shown in Fig. 4, the construction is substantially the same as shown in Figs. 1 and 6, first above described, except that 40 the gland bushings 30 are made of larger external diameter and seated in holes of correspondingly larger diameter in the end panels. The external diameter of these bushings and the diameters of the holes 21 in the end panels in 45 which they bear are slightly larger than the diameter of the drip rings 15 and 16 on the tubes, the holes in the end panels being large enough to permit the drip rings and the drip strip 14 on the tubes to pass through the holes in the 50 end panels. In this construction, therefore, when the connectors at the opposite ends of a tube have been disconnected therefrom, the tube is adapted to be withdrawn endwise through the holes in the panels, for removing the tube.

In tubular surface heat exchangers of the character hereinabove described, employing tubes of considerable length, it is desirable to provide means to prevent the middle portions of the tubes from sagging and to preserve the parallelism and uniform spacing of the tubes. This may be accomplished, as shown in Figs. 1 and 3, by providing at the middle portion of the exchanger upright tube bracing or spacing bars 31 which are releasably clamped against the opposite sides of the tubes so as to hold the tubes rigid by thumb screws or the like 32, which permit the ready removal of the brace bars when it is desired to remove one or more of the tubes. The bars 31 may be formed with segmental circular seats in their inner sides to receive and accurately space the tubes.

By the constructions described, the tube supporting bushings fit loosely enough in the holes 21 of the supports 11 to adapt them to move 75

lengthwise in the holes, and since the connectors are separate or disconnected from each other except through the instrumentality of the tubes, they can move independently relatively to one another in the expansion and contraction of the tubes if the expansion or contraction of different tubes is unequal and thus prevent destructive strains on the device. Nevertheless, the tubes are retained in vertical alignment and in the proper spaced relationship.

I claim as my invention:

1. A tubular heat exchanger for liquids comprising separate parallel tubes arranged for the flow of a liquid over their outer surfaces, tube supports having holes of larger diameter than the tubes through which the opposite ends of the tubes extend, a separate connector joining one end of each tube to the corresponding end of an adjacent tube for the passage of a fluid through the tubes, said connectors being arranged outwardly beyond said supports and removably attached to the tubes, and bushings surrounding the tubes in the holes in said supports for supporting the tubes in the holes, one of said tubes when detached from the connectors at its opposite ends being removable through its supporting holes without disturbing the remaining tubes and connectors.

2. A tubular heat exchanger for liquids comprising separate parallel tubes arranged for the flow of a liquid over their outer surfaces, tube supports having holes of larger diameter than the tubes through which the opposite ends of the tubes extend, a separate connector joining one end of each tube to the corresponding end of an adjacent tube for the passage of a fluid through the tubes, said connectors being arranged outwardly beyond said supports and removably attached to the tubes by means including end rings on the tubes of an outside diameter small enough to pass through said supporting holes, and bushings surrounding the tubes in said holes for supporting the tubes in the holes, any one of said tubes when detached from the connectors at its opposite ends being removable through its supporting holes.

3. A tubular heat exchanger for liquids comprising separate parallel tubes arranged for the flow of a liquid over their outer surfaces, tube supports having holes of larger diameter than the tubes through which the opposite ends of the tubes extend, a separate connector joining one end of each tube to the corresponding end of an adjacent tube for the passage of a fluid through the tubes, said connectors being arranged outwardly beyond said supports and removably attached to the tubes, and bushings surrounding the tubes in the holes in said supports for supporting the tubes in the holes, said tubes having outwardly projecting drip member thereon between said supports but spaced therefrom sufficiently to permit a tube to be shifted through the hole adjacent one of its ends far enough to withdraw the opposite end of the tube from the other hole, any one of the tubes when detached from the connectors at its opposite ends being removable through its supporting holes.

4. A tubular heat exchanger for liquids comprising separate parallel tubes arranged for the flow of a liquid over their outer surfaces, tube supports having holes of larger diameter than the tubes through which the opposite ends of the tubes extend, and a separate connector joining one end of each tube to the corresponding end of an adjacent tube for the passage of a fluid

through the tubes, said connectors being arranged outwardly beyond said supports and removably attached to the tubes by means including gland nuts surrounding the tubes and each extending into the hole in the adjacent support and forming a bushing for supporting the tube in said hole, any one of the tubes when detached from the connectors at its opposite ends being removable through its supporting holes.

5. A tubular heat exchanger for liquids comprising separate parallel tubes arranged for the flow of a liquid over their outer surfaces, tube supports having holes of larger diameter than the tubes through which the opposite ends of the tubes extend, a separate connector joining one end of each tube to the corresponding end of an adjacent tube for the passage of a fluid through the tubes, said connectors being arranged outwardly beyond said supports, and gland nuts surrounding said tubes and cooperating with external rings on the tubes for removably attaching the tubes to the connectors, each gland nut extending into the hole in the adjacent support and forming a bushing for supporting the tube in the hole, any one of the tubes when detached from the connectors at its opposite ends being removable with the rings thereon through its supporting holes.

6. A tubular heat exchanger for liquids comprising separate parallel tubes arranged for the flow of a liquid over their outer surfaces, tube supports having holes of larger diameter than the tubes through which the opposite ends of the tubes extend, a separate connector joining one end of each tube to the corresponding end of an adjacent tube for the passage of a fluid through the tubes, said connectors being arranged outwardly beyond said supports and removably attached to the tubes, and bushings surrounding the tubes in the holes in said supports for supporting the tubes in the holes, said tubes having outwardly projecting drip members thereon between said supports, and the holes in said supports being of such diameter that any one of the tubes when detached from the connectors at its opposite ends is removable with the drip projections thereon through its supporting holes.

7. A tubular heat exchanger for liquids comprising separate horizontal tubes arranged one above another for the flow of a liquid downwardly over their outer surfaces, stationary upright supports adjacent the opposite ends of the tubes having holes of larger diameter than the tubes through which the ends of the tubes extend, a separate connector joining one end of each tube to the corresponding end of an adjacent tube for the passage of a fluid through the tubes, said connectors being arranged outwardly beyond said supports, and means removably attaching said connectors to the tubes including gland nuts surrounding the tubes and extending into the holes in said supports and forming bushings for supporting the tubes in the holes, said tubes having external enlargements adapted to pass through said holes when the bushings are withdrawn therefrom, any one of said tubes when detached from the connectors at its opposite ends being removable through its supporting holes.

8. A tubular heat exchanger for liquids comprising separate parallel tubes arranged for the flow of a liquid over their outer surfaces, stationary tube supports adjacent the opposite end of the tubes and having holes of larger diameter than the tubes through which the opposite ends of the tubes extend, a hollow connector joining

one end of each tube to the corresponding end of an adjacent tube for the passage of a fluid through the tubes, said connectors being arranged outwardly beyond said supports and removably attached to the tubes, and bushings surrounding the tubes in the holes in said supports for supporting the tubes in the holes, said bushings being withdrawable from said holes, and said tubes having external lateral end projections of a size 5 to pass through said holes when said bushings

are withdrawn therefrom and also having external projections between said supports and spaced therefrom sufficiently to allow either end of the tubes to be withdrawn inwardly from the holes in the adjacent support, any of said tubes when detached from the connectors at its opposite ends being removable through its holes in said supports independently of the remaining tubes. 5

HARVEY FELDMEIER. 10
